BROWN, BOVERI & CIE., OF BADEN, SWITZERLAND.

ELECTRICAL DISTANCE CONTROL.

992,628.

Specification of Letters Patent. Patented May 16, 1911.

Application filed September 24, 1909. Serial No. 519,452.

To all whom it may concern:

Be it known that I, ALBERT AICHELE, a citizen of Switzerland, and residing at Wiesenstrasse, Baden, Canton Aargau, Switzerland, have invented a certain new and useful Improved Electrical Distance Control, of which the following is a specification.

The invention relates to electrical distance controls.

The object of the invention is to provide an improved form of such devices which shall be applicable among other uses, to a multiple unit control system for electrically 15 propelled trains and the like.

The invention includes the novel arrangement of parts and elements hereinafter described and defined by the appended claims.

In Figure 1 is illustrated diagrammatically and by way of example an application of the present method to single phase alternating current plants. Fig. 2 shows by way of example an accumulator distance control. Fig. 3 shows an application of the 25 present invention to three phase circuits. Figs. 4 and 5 show further modifications applicable to alternating current systems. Fig. 6 shows a modification applicable for high tension systems and Fig. 7 indicates an 30 application of the present invention to the multiple control of electrically operated vehicles.

Referring to Fig. 1, A and B represent the main conductors carrying the current, 35 M' is a motor to whose terminals can be applied various voltages by means of the distant control. An autotransformer T is connected across A and B. Leads are provided at 6 different points of its windings, 40 which terminate in contact pieces numbered 1 to 6. These leads are further connected to the contact pieces 1' to 6' of the controlling element S, by separate conductors 1' to 6'. The sliding member, R, can be 45 moved over the contact pieces, 1 to 6 of the transformer T by turning the screwed spindle U passing through the same. This rotation is performed by a small auxiliary motor, whose rotor E is mounted directly 50 on the screwed spindle U, its exciter windings being connected to the transformer winding at the points H and K. The motor M' which is to be driven at various voltages by means of the distant control is connected

on the one hand to the main conductor B, 5 and on the other hand with a strip V which is permanently in contact with the sliding member R. One brush M of the auxiliary motor E is connected to the above strip V, the other brush N, being in communication 60 with the contact piece P of the controlling apparatus S, through the conductor, L.

In Fig. 1 the sliding member, R, is shown in contact with the stud, 2. In this case the main motor M', is subject to a voltage 65 corresponding to the studs, 1 and 2. If the voltage at its terminals is to be increased to that corresponding to the studs 1 and 4, the point P of the controlling element is connected with the contact stud 4'; for 70 example by suitable adjustment of a contact cylinder which is shown developed in the plane of the paper in the drawing. A current now flows from the branch 4 of the transformer T through the conductor 4', 75 to the contact stud, 4', thence by way of the stud P through the conductor L to the brush N, through the rotor E and the brush M to the strip V and thence through the sliding contact member R to the point 2 of 80 the transformer T. The rotor E of the auxiliary motor is therefore in circuit with the points 2 and 4 of the transformer T, and the current passing through it causes it to rotate in such a direction that the sliding contact member R, moves onto the contact piece, 4. When this position is reached, the rotor E, of the auxiliary motor loses the current and stops. The motor M', is now in circuit with the points 1 and 4 of 85 the transformer T and receives a corresponding voltage. If the contact cylinder of the controlling element be now brought back on to the point 3'' a current will pass through the rotor E of the auxiliary motor 90 in the reverse direction, and the latter will therefore turn in the opposite direction until the sliding member R, reaches the contact piece, 3. The motor M' is now subjected to a voltage corresponding to the 95 points 1 and 3. In this manner the sliding contact member, R, automatically follows any desired adjustment of the controlling member, S, the motor E receiving a current in one or the other direction according as 100 the new position of the member S is above or below the previous one. The adjustment of the sliding member R is therefore posi-

tive as far as that point to which the controlling member is set, and the adjustment takes place as soon as a current passes through the main conductor A and B, even 5 when no current is passing at the time of setting the controlling member.

Referring to Fig. 2 which illustrates diagrammatically the application of the present method for controlling an accumulator regulator from a distance in which corresponding parts are lettered similarly to those of Fig. 1 the battery of accumulators B or a part thereof replaces the transformer. One or more cells may be connected to and between each pair of contacts 1 to 11. A continuous current motor serves as the auxiliary motor in this case, whose armature E is connected through the brushes M and N to the strip V, and by way of the conductor 10 L to the contact P of the controller respectively, its field windings G receiving their current from the cells between the points X, Y. That part of the sliding member, R, resting on the contacts 1 to 11 is constructed in two parts as is usual in the case of cell switches, and is provided with a resistance W. The contacts 1 to 11 of the cell regulator are connected through the conductors, 1' to 11' to the corresponding contacts, 1'' to 11'' of the controller S. The manner in which this arrangement acts is obvious from what has been said regarding that shown in Fig. 1. In order to apply this method to three phase circuits, the arrangement indicated in Fig. 3 can be used. The three phase current is supplied through the conductors A, B, and C. An autotransformer is in circuit with each of the latter, whose windings are provided with 15 branches connected to the contact pieces 1 to 6 in each phase. A sliding member R in each phase moves over the latter and also rests on a strip V. The conductors N, O and Z lead from these strips to the motor M', whose terminal voltage is to be regulated from any desired point by means of the controlling member S. For this purpose the contact pieces 1 to 6 of the phase C are connected through the conductors 1' to 6' 20 to the contacts 1'' to 6'' of the controlling member S.

The movement of the three sliding members R is performed by means of the rotation of the three screwed spindles U which are coupled together mechanically. They are driven by the motor E mounted on the middle spindle. In the present example a two phase induction motor is used the phase G of whose stator windings is connected to the 25 point X, Y of the interlinked voltage of the phases A and B, while its other phase D only receives current while the position of the sliding members R does not correspond with the setting of the controlling member.

60 In the circuit of the phase D of the stator

windings is also connected the coil of an electromagnet Q, whose armature interrupts the current of the phase G of the stator windings at the contact I under the influence of the spring K. This arrangement 70 operates in the following manner whenever the position of the sliding contact members, R, which are positively coupled together for all phases does not correspond to the setting of the controlling member, S, a current 75 passes through the conductor L to the phase D of the stator of the auxiliary motor E, and excites this phase of the stator as well as the electromagnet Q by means of its coil F. The magnet attracts its armature 80 and thereby closes the circuit of the phase G of the stator. The auxiliary motor therefore works as a two-phase motor and changes the position of the sliding members R until the current ceases to flow in the phase D of 85 the stator. This takes place when that contact corresponding to the setting of the controller S is reached by the sliding members R. Thereupon the electromagnet Q releases its armature and breaks the current of the 90 phase G in the stator of the auxiliary motor E, so that the latter remains completely cut out, and only comes into operation again after further setting of the controlling member S. A shunt commutator motor for 95 alternating current can also be used as the auxiliary motor instead of an induction motor. This arrangement is illustrated diagrammatically in Fig. 4. The corresponding parts have the same reference letters as 100 in Fig. 3. In this case it is preferable not to join the field excitation of the auxiliary motor to that phase whose current passes through the rotor of the motor, as in this manner a larger turning moment of the motor 105 can be obtained.

In the present example the exciter windings G are connected at the points X, Y, to the phase C, the current for the armature E of the motor being taken from the phase B. 110 The arrangement and method of operation of this form of the invention is obvious from what has been said above regarding Fig. 3. In using this arrangement for alternating current plants, the connections may also be 115 carried out with the use of two transformers in such a manner that one of them carries the working current and the other merely the controlling current. Such a modification for single phase circuits is illustrated 120 diagrammatically in Fig. 5. The main conductors supplying the current are lettered A and B. An autotransformer T is connected across these, provided with 6 leads with corresponding contact pieces 1_o to 6_o 125 connected by conductors 1' to 6' to the corresponding contacts 1'' to 6'' in the controller S. The method of operation of this arrangement is obvious from what has been said with reference to the other examples. 130

The armature E of the motor receive current in consequence of the difference in pressure produced between the corresponding points of the transformer windings T and T₀ resulting from a difference in the setting of the sliding member R and the controller S; and displace the sliding member by rotation of the screwed spindle toward that contact piece of the transformer T corresponding to the setting of the controller S.

In applying the present system to high tension plants, the connection between the controlling member S and the member to be controlled, can be effected by means of a transformer T' T'' connected to the auto-transformer T, the high tension current having no access to the member to be controlled. For this purpose the arrangement of connections indicated by way of example in Fig. 6 can be used. High tension current is supplied through the conductors A and B. The high tension autotransformer T is connected across these conductors and is provided with branches terminating in contact pieces 1₀ to 6₀. The sliding member R moves over the latter, being continuously in contact with the strip V, and is displaced by means of the single-phase commutator motor driving the screwed spindle U.

The high tension windings T' of the transformer T' T'' are connected across the ends of the high tension transformer T at the points D and F by means of the conductors D' and F'. The low tension windings T'' of the former are provided with 6 branches corresponding to the branches 1₀ to 6₀ of the autotransformers T, and ending in contact pieces 1 to 6 which are in communication with the corresponding contacts 1'' to 6'' of the controlling member, through the conductors 1' to 6'. A second sliding member R' rigidly connected by means of an insulating piece I to the sliding member R which moves over the contacts 1₀ to 6₀ and the strip V, is moved simultaneously with the said member R on rotation of the screwed spindle U, over the contacts 1 to 6 and the strip V'. The armature E as well as the exciter windings G of the auxiliary motor are connected to the low tension side of the transformer T' T''. The armature E is connected through the brush M to the strip V', which in turn is in communication with the low tension windings T'' through the sliding member R', and through the brush N and the conductor L with the contact P of the controller. The exciter windings G on the contrary are connected to the ends of the low tension windings at the points X and Y. The method of operation of this arrangement is obvious from what has been said above with reference to the first-mentioned example. The adjustment of the sliding members R and R' combined together, is effected by the action

of the difference of pressure produced between the corresponding contacts of the transformer windings T' by a difference between the setting of the controller S and the position of the sliding member R'. 70

The advantages which the application of the new system offers, are especially apparent in applying it to the multiple control of electrically operated vehicles. In this case only a single conductor is necessary for connecting the separate vehicles. Fig. 7 shows by way of example, an arrangement for such an application of the system. Two vehicles F₁ and F₂ each with two auxiliary motors, namely E₁ E₂, and E₃ E₄ respectively, and each with two controllers, namely S₁, S₂, and S₃, S₄, respectively. The working transformers T₁, T₂, T₃, and T₄, provided with branches and contacts 1 to 5, each receive current separately through the trolleys A₁, A₂, A₃, and A₄, and are connected in parallel among themselves, the ends of the same being earthed at K through the conductors K₀. All the auxiliary motors are connected in parallel among themselves 80 in a similar manner, the brushes M₁ M₂ M₃ M₄ being connected to the common conductor L which is coupled at L₀ for the two vehicles. The points P₁ P₂ P₃ P₄ of all the controllers S₁ S₂ S₃ S₄ respectively are in communication with one another through this conductor L. The exciter windings G₁ G₂ G₃ G₄ of the auxiliary motors E₁ E₂ E₃ E₄ respectively are connected to the transformers T₁ T₂ T₃ T₄ at suitable points. 90 The motors M₁ M₂ M₃ M₄ of the vehicles which are to be controlled are joined up to the strips V₁ V₂ V₃ V₄ on the one hand and are earthed at K through the conductors B₁ B₂ B₃ B₄ respectively. By means of such an arrangement, any desired number of driving motors on any number of vehicles can be positively controlled from one point. 100

The method of operation of the arrangement illustrated in Fig. 7 is as follows. Suppose all the controllers S₁ to S₄ are set to their starting positions, so that in each case the contact 5'' is joined to the contact P, that is, the common conductor L and the brush M and N of the auxiliary motor connected to the same are earthed through the conductor K₀. The sliding members R₁ R₂ R₃ R₄ are in corresponding positions on the contacts 5. If now by suitable setting of the controller S₁, the contact 4'' be connected with P₁, all the armatures E₁, E₂, E₃ and E₄ of the auxiliary motors receive current simultaneously, their brushes M₁ M₂ M₃ M₄ being connected through the common conductor L, the conductor L₁, the point P₁ and the conductor 4' to the contact 4 of the transformer T₁ while their brushes N₁ N₂ N₃ N₄ are in communication with the contacts 5 of the transformer through the sliding members R₁ R₂ R₃ R₄. The auxiliary 110

115

120

125

130

motors therefore receive current under the influence of the difference of pressure between the contacts 4 and 5 of the transformer T_1 and move the sliding members 5 onto the contact 4 by rotation of the screwed spindle U_1, U_2, U_3, U_4 . As soon as the sliding member R has reached this contact, the corresponding motor loses the current and stops. All the driving motors M_1, M_2, M_3, M_4 of the 10 vehicles coupled together in this manner, being each connected to the strips V_1, V_2, V_3, V_4 , receive a working pressure at their terminals corresponding to the branch 4 of the transformers T_1, T_2, T_3, T_4 . In this manner 15 the sliding members R_1, R_2, R_3, R_4 on all the transformers follow the movement of the controller S_1 so that the working pressure of all the motors can be positively controlled from this single point.

20 The number of the vehicles to be controlled together can be increased as desired, only one connection being required between any two vehicles. The 4 driving motors can of course be controlled from S_2, S_3 or S_4 as 25 well as from S_1 . The present system can of course be used not only for controlling transformers but also for operating resistances, switches, or any other desired apparatus.

30 Having now described our invention, what we claim as new and desire to secure by Letters Patent is:

1. In combination, an element to be controlled, a sectional transformer serving said element, contacts connected to the sections of said transformer, an adjustable member to connect any of aforesaid contacts to said element, a master controller, contacts on same, connected to corresponding contacts 35 on said sectional transformer, a motor adjusting device for said adjustable member operated by the closing of contacts on said controller to move said adjustable member into co-action with the corresponding transformer contacts.
2. In combination, a motor, an auto-transformer serving said motor, contacts connected to a plurality of points on said auto-transformer, a conductor connected to said motor, an adjustable member connecting any one of said transformer contacts to said conductor, a master controller, contacts on same connected to the transformer contacts, 40 a screw device for adjusting aforesaid member, and an auxiliary motor operating same and connected to aforesaid conductor and to said controller.
3. A multiple control system for electrically operated vehicles, comprising a plurality of motors, an equal number of auto-transformers connected in parallel among themselves, and further each connected to a trolley wire and to earth, contacts connected to a number of points on each of 45 said auto-transformers, a conductor corre-

sponding to each auto-transformer and each connected to a corresponding driving motor, an adjustable member coacting with each of said conductors and said contact sets, a controller for each transformer, contacts 70 on said controllers connected to the corresponding transformer contacts, a motor adjusting device for each of aforesaid adjustable members connected to the aforesaid conductor and to the controller. 75

4. A distance control system comprising a controlling member and a member to be controlled, contacts on said controlling element, contacts on said controlled element, a plurality of conductors joining said contacts 80 of controlling element to those of the controlled element, an adjusting member adapted to coact with any of the contacts of said controlled element and thus to effect control, and adjusting means operable by a 85 current produced by a relative displacement of said adjusting member and aforesaid controlling element.

5. A distance control having a motor, two sets of contact terminals to which correspondingly variable voltages are supplied, switch arms to engage the respective sets of terminals one of which is operated by the motor in accordance with the direction and extent of manual movement of the other 90 arm the motor being connected to said motor operated switch, in which the rotor and stator of the motor are electrically distinct; as set forth. 95

6. In combination an auto-transformer, 100 spaced contacts on said transformer, a master controller, contacts on same respectively connected to transformer contacts, a contact disposed in proximity to said transformer contacts, a switch arm traversing the latter and permanently in connection with aforesaid contact, a motor operator for aforesaid switch arm electrically connected to a contact of said master controller and to aforesaid contact, and having its stator 105 and rotor electrically distinct, as set forth. 110

7. A multiple control system for electrically operated vehicles comprising a plurality of motors; an equal number of current collectors; a conductor with which each of said collectors co-acts; a plurality of autotransformers equal in number to the number of motors, and each connected between one of the collectors and a common return; 115 spaced contacts on each of said auto-transformers; a conductor corresponding to each of said auto-transformers, each motor being connected between one of said conductors and a common return; an adjustable contact member capable of co-acting with each of the spaced contacts and corresponding conductors to effect connection of any of the contacts to the conductor; a master controller corresponding to each of said 120 transformers; contacts on same; connections 125

from each of said contacts to one of said transformer contacts; a further contact on each of said controllers; a motor adjusting device for each of said adjustable contact members, the motors of each of which are electrically connected to the corresponding conductor and to the corresponding further contact on the master controller; and an electrical connection connecting all of aforesaid further contacts. 10

In testimony whereof, I have affixed my signature in presence of two witnesses.

ALBERT AICHELE.
